CLAIM

The ornamental designs for tire balancers (weights), as shown and described.

DESCRIPTION

FIG. 1 is a perspective view of the first embodiment my tire balancer (weights);

FIG. 2 is a top view of the first embodiment;

FIG. 3 is a first end view of the first embodiment, the second end view being a mirror image thereof;

FIG. 4 is a left side view of the first embodiment, the right side view being a mirror image thereof;

FIG. 5 is a perspective view of the second embodiment of my tire balancer (weights);

FIG. 6 is a top view of the second embodiment;

FIG. 7 is a first end view of the second embodiment, the second end view being a mirror image thereof; and,

FIG. 8 is a left side view of the second embodiment, the right side view being a mirror image thereof.

All other surface(s) or portion(s) of the tire balancer (weights) not shown in the figures or otherwise described in the specification form no part of the claimed design.
